UNITED STATES PATENT OFFICE.

JOHN VINTILA, OF CLEVELAND, OHIO.

AEROPLANE.

1,158,594.

Specification of Letters Patent.

Patented Nov. 2, 1915.

Application filed June 1, 1915. Serial No. 31,397.

To all whom it may concern:

Be it known that I, JOHN VINTILA, subject of the Emperor of Austria-Hungary, residing at Cleveland, in the county of 5 Cuyahoga and State of Ohio, have invented certain new and useful Improvements in Aeroplanes, of which the following is a specification.

This invention relates to aeroplanes of 10 the screw propeller type, characterized by improvements with respect to the steering devices.

In the drawings—Figure 1 is a side elevation of the machine. Fig. 2 is a front elevation. Fig. 3 is a top plan view. Fig. 4 is a detail of the rear supporting wheel. Figs. 5 and 6 are details of frame joints. Fig. 7 is a detail in perspective of the front steering arrangement. Fig. 8 is a detail of a 20 modified rear wheel structure. Fig. 9 is a detail in perspective of a spring connection between the front wheel and the frame.

Referring specifically to the drawings, 6 indicates a main tubular longitudinal strut 25 located at the median line of the machine and supporting the main plane 7. The central strut supports, at its front end, the horizontal rudder 8 and the vertical rudder 9. The front propeller 10 has a hub mounted 30 on the strut 6, in front of the plane, and the rear propeller 11 has a hub mounted on said strut at the rear of the main plane, said strut thereby supporting both of the propellers. A horizontal tail plane 12 is carried at the rear end of the strut. The strut 6 is part of the main frame which also comprises inclined front bars 13 and inclined rear bars 14 jointed to front and rear standards 70 and 71, the joints being shown in 35 Figs 5 and 6 and having openings 72 for the strut 6 and openings 73 for the bearings of the drive shaft 19 which extends lengthwise under the strut. The propellers 10 and 11 turn on the bearings described and each 40 45 of the hubs has a gear 17 which meshes with a pinion 18 on the shaft 19 which is driven from the engine 20 by a chain drive 21 and suitable sprockets. The frame is mounted on two front wheels 26 and a rear 50 wheel 22. The rear wheel is carried by a fork 23 pivoted at 23^a to a keel 15 which is supported by braces 15^a from the bars 13 and 14, and a spring 25 is connected between the fork 23 and the keel 15 to cushion the 55 shock of landing. In the modified form shown in Fig. 8 the fork 23^b is pivoted at

23^c to a strut 23^d depending from the keel 15, and has a rod 23^e which works through a guide 15^b in the keel, with a spring 25^a coiled around the rod to cushion the impact, 60 the front end of the fork being free to swing to and from the keel as shown in dotted lines in Fig. 8. The front wheels are carried at the outer ends of an axle 27 which is supported by radius rods 28 pivoted to the 65 keel, and allowing the wheels to yield up and down. The outer ends of the axles are connected to bars 29 which have T heads 29^a at their upper ends which slide in slotted guides 30 fixed to the front bars 13, as 70 shown in Fig. 9. This movement is resisted when landing by tension springs 31 connected between the bars 29 and the bars 13, and these springs serve to take up the shock of landing, by permitting relative movement of the bars 29 and 13. 75

The rudders are operated by a steering column and wheel 32 which has both rotary and lateral movements. The rotary movement controls the horizontal rudder 8, which is hinged at 33 to the cross bar 48 at the front end of the strut 6, the movement being communicated by cables 34 and 35 which are connected to the rudder and pass over pulleys 36 and 37 in the vertical bar 80 at the 80 front end of the strut 6 and thence pass into the hollow strut 6 through holes at 38 and thence over sheaves 39 and out through an opening in the strut to connection with the winding drum 40 on the steering column 32. 85 The vertical rudder 9 is in two parts, pivoted at 41 and 42 to the post 80, and connected to a slotted guide 43 through which the strut 6 extends. The outer ends of this slotted guide are connected to cables 44 and 45 which pass over pulleys 46 and 47 at the 90 ends of the horizontal cross bar 48 and thence around pulleys 49 and 50 on the front bar of the plane 7 to connection at 90 to the column 32, the lateral movement of 100 which thereby swings the rudder 9 with its guide piece 43.

51 is a supply tank for fuel and oil, and 52 is a canvas-covered body for the aviator and passengers if any, said body resting on the keel 15. The main plane, the central strut 6, and the other parts of the frame, are 105 suitably connected by guy wires 100.

It will be seen that the propellers, rudders and main plane are all carried by a single 110 longitudinal hollow strut 6 located at the middle line of the machine, and the hori-

horizontal rudder is controlled by cables passing through said strut. Also the spring supported wheels serve to cushion any shock incident to landing. The simplicity and compactness of the propeller driving gearing are important features of advantage.

What I claim as new is:

The combination with a longitudinal strut, of a horizontal rudder hinged to the 10 end of the strut, a post at the end of the strut, a vertical rudder comprising two parts hinged to the post respectively above and below the strut, with a space between

the parts so that they may swing across the strut, a slotted guide to which said parts are 15 attached, the strut extending through the slot, and means to operate the rudders, including cables connected to said slotted guide.

In testimony whereof, I affix my signature 20 in presence of two witnesses.

JOHN VINTILA.
